(74) Attorney, Agent, or Firm — Charlena Thorpe, Esq.; F. Wayne Thompson, Jr.; The Law Office of Charlena Thorpe, Inc.

CLAIM

The ornamental design for a posture-assisted yoga towel, as shown and described.

DESCRIPTION

The sole FIGURE is a front view of a posture-assisted yoga towel.

The border of the posture-assisted yoga towel forms a part of the design and comprises dot shaped markings.

The posture-assisted yoga towel is flat and planar. Depth or thickness forms no part of the claimed design.
